SLEEVE LAYER

Donald W. Sessions, Lansing, Mich.

Application October 1, 1947, Serial No. 777,319

12 Claims. (Cl. 223—57)

1

This invention relates to mechanism designed and adapted for the purpose of ironing shirts or like garments and more specifically comprises a novel arrangement to efficiently iron the sleeves of such garments to greatly step up productive results along these lines of endeavor.

The mechanism herein disclosed and described is similar in many respects to the device of a like nature comprising the subject matter of an application filed in the name of the instant inventor on December 12, 1946, bearing the Serial No. 715,831, now Patent No. 2,499,931, issued March 7, 1950, of which the present application is a continuation in part.

It is one of the main objects of this sleeve layer to provide a means that may be used in combination with one or two conventional garment presses for the purpose of quickly and efficiently placing the sleeves of a shirt in pressing position with respect to an adjacent press or presses. With the dual press arrangement, one sleeve layer will function in the capacity to simultaneously bring both sleeves of a single shirt or other garment into operative pressing position with respect to both presses.

Another object of the present invention is to provide a means of this type which will automatically position the sleeves in an ironing position and then into stripping or receiving position with little effort on the part of the operator of the ironing combination.

A still further object of the invention is to provide a sleeve layer of this kind which will function during operation to bring the sleeves into horizontal positions and in proper alignment with the bucks of the presses for engagement by the ironing shoes, and which layer also functions to automatically bring the shirt sleeves into convenient positions for stripping ironed sleeves and to receive unironed sleeves at stations removed from the heated ironing shoes with the latter disposed in their inoperative and raised positions.

Another object of this invention is to incorporate further means for easy actuation by the operator which will releasably lock the sleeve holders of the layer in their charging positions for the convenience and feasibility of the operator. Although similar locking means could be used to retain the sleeve holders in operative ironing position, it is preferable to leave the sleeve holders free to better accommodate the sleeves to the contours of the bucks and heated shoes.

The use of a single hand control for the sleeve holders further enhances the efficiency of the sleeve layer. This single control also releases

2

the sleeve layer parts from their locked positions through actuation in one direction, while rotation or movement of the control in another direction actuates the sleeves and their holders into operative press engaging positions.

The sleeve holders are preferably semi-flexible to facilitate easy reception of the sleeves and to provide for the necessary flexing of such holders between the heads and bucks of the presses 10 during the pressing operation. This flexibility in the holders also takes care of certain variations in the sleeve sizes.

The entire device is compactly constructed for ease of operation and to concentrate the working 15 zone into a relatively small area to eliminate all unnecessary movements or to cut down lengths of movements by the operator during the shirt sleeve ironing period.

All other objects and advantages relating to 20 the sleeve layer of the present invention and its mechanical working parts shall hereinafter appear in the following detailed description having reference to the accompanying drawings forming a part of this specification.

25 In the drawings:

Fig. 1 is a fragmentary plan view of the sleeve layer as combined for use between two conventional heated shoe presses and as the same would appear with the sleeve holders and associated 30 parts in operative pressing positions;

Fig. 2 is a side elevational view of the sleeve layer as seen approximately along the line 2—2 in Fig. 1 showing the supporting bracket in section and with the left hand buck of Fig. 1 omitted;

35 Fig. 3 is a detail cross sectional view of the rear portion of the sleeve layer with the adjacent bucks indicated in elevation, the view being taken substantially along the plane of the line 3—3 in Fig. 1;

40 Fig. 4 is a cross sectional view to illustrate further details of construction of the operating mechanism of the sleeve layer, this view being taken substantially along the line 4—4 in Fig. 2; and

45 Fig. 5 is a fragmentary enlarged detail cross sectional view taken substantially along the plane of the line 5—5 in Fig. 2 to illustrate the locking mechanism utilized in this particular form of construction of sleeve layer.

Referring to Figs. 1 and 2, the sleeve layer is shown in combination with a pair of heated shoe presses having bucks 1 and 2 adjacently arranged to be contacted either simultaneously or individually by their respective movable ironing shoes

3 and 4. Each buck 1 and 2 is supported by portions of the press standards 5 and 6, and these main parts of the presses are suitably spaced to position the presses as a whole by means of a bracket 7 that is conveniently fastened to each of the press standards 5 and 6. Bracket 7 is also used as a bridge between presses for the purpose of supporting the sleeve layer and to position the same in its proper operative relation with respect to the two presses.

The main frame of the sleeve layer consists of a hollow base 8 secured to the bracket 7, the base supporting a pair of parallel overhanging frame bars 9 and 10 by means of cleats 11-11 and 12-12, respectively, although any other suitable means may be used to mount the bars upon said base.

A gear box 13 is mounted upon bars 9 and 10, and upon the forward end of the base 8. This box 13 contains the same general mechanism as does the gear box in the copending prior application of which this case forms a continuation in part. As seen in Fig. 4, the gear box 13 has an operating shaft 14 mounted for rotation in the gear box walls and projecting outwardly for fixed connection with a hub 15 having a manual hand operated control handle 16 secured thereto. A drive gear 17 is keyed to the shaft 14 by means of the key 18 (Fig. 4), the key being free to slide in the keyway 19 in shaft 14 so that the shaft can be endwise shifted relatively to the housing of the gear box 13.

The purpose of the shiftable shaft 14 is to introduce an indexing or detent means which will stop the handle 16, and its connected parts, in a fixed position to dispose the sleeve holders in a predetermined position while covering the same with the sleeves of a shirt or while stripping the sleeves therefrom during the active operation of the device.

The detent or stop means is best seen in Fig. 5 and comprises a collar 20 secured by a pin 21 to shaft 14, and the collar 20 has a stop pin 22 on the face thereof for engaging in an opening 23 formed in the front wall 24 of the gear box 13. A suitable expansion spring 25 is carried upon shaft 14 and is interposed between the hub 15 and the surface of the wall 24 for the purpose of normally urging the shaft 14 endwise out of the housing of the gear box 13 and in a direction to cause pin 22 stay in opening 23 or to abut the inner surface of the gear box wall 24 when the pin 22 is not in register with the opening 23. A push on handle 16 will move pin 22 out of the wall opening 23 and any rotation of the handle 16 will throw the pin out of registry with respect to the opening 23 permitting free operation of the parts controlled by handle 16.

Referring again to Fig. 4, gear 17 meshes with an idler reverse gear 26 carried upon a stub shaft 27, and both gears 17 and 26 mesh with oppositely rotatable gears 27 and 28 respectively which are secured by set screws 29 and 30 to the gear box ends of the sleeve holder operating stub shafts 31 and 32.

A second pair of shafts 33 and 34 are swingably and rotatably connected with shafts 31 and 32 respectively by means of the universal joints 35 and 36. The outer and swingable ends of shafts 33 and 34 are guided in openings 37 and 38 formed in uprights 39 and 40 of a cross bracket 41 fastened to the rearward ends of the bars 9 and 10 and extending therebetween as best seen in Fig. 3 of the drawings. Bracket 41 is further provided with a cross brace 42 having a flat top 75

surface 43 adapted for coaction with a pair of lifting cams 44 and 45 which are each fixedly secured to the shafts 33 and 34 respectively.

Each of the shafts 33 and 34 carries a sleeve holder 46 and 47, and as seen in Fig. 2, each holder consists of a semi-flexible open frame 48 terminating in a lower cross bar 49 having alternately oppositely formed fingers 50 and 51 connected therewith to engage circumferential disposed portions of the shafts 33 and 34 and to be secured thereto by screws 52 and 53 or in any other desirable and preferably removable manner. A suitable fabric envelope 54 is used to cover each sleeve holder and may be fastened thereto by means of a draw string 55 associated with the open end 56 of the envelope, suitable notches 57 and 58 being formed in the frame 58 adjacent the bottom portion to provide means which will prevent slippage of the draw string 55 and its connected envelope.

During the stripping and loading of the sleeve holders 46 and 47, the latter are disposed in the position indicated in Fig. 2—upwardly and forwardly tilted to be safely spaced from the hot shoes of the presses. Fig. 3 shows the same relationship of the sleeve holders in dot and dashed lines, the sleeve holders diverging upwardly and laterally outwardly to provide suitable clearance between the holders to conveniently accommodate the body part of the shirt while arranging the sleeves over the holders. These positions of the holders are positively determined by the registry detent means shown in Fig. 5 and also by the angular dispositions of the sleeve holder shafts 33 and 34 brought about through the cams 44 and 45 being in erect positions with respect to the surface 43 of the cross brace 42 of the bracket 41.

To lower and rotate the sleeve holders into aligned and oppositely outwardly extended positions over each of the press bucks 1 and 2 and into a common horizontal plane, the operator moves handle 16 slightly toward the gear box 13 and then rotates the same in a clockwise direction as viewed in Fig. 4 to revolve gears 21 and 28 in a direction to swing the sleeve holders 46 and 47 toward the bucks and into the full line positions best shown in Figs. 1 and 3. After the press heads 3 and 4 have been lowered to press the sleeves carried by the sleeve holders, the operator reverses the rotation of the handle 16 to again bring the mechanism into the positions shown in full lines in Fig. 2 and dot and dashed lines in Fig. 3.

During the rotation of the stub shafts 31 and 32, shafts 33 and 34 are brought from their inclined positions in Fig. 2 downwardly into parallel horizontal positions as shown in Figs. 1 and 3, the inclination of the shafts being brought about through the attached cams 44 and 45 coacting upon the surface 43 of the cross brace 42 and through the vertical guidance of the openings 31 and 39 in the uprights 39 and 40, the action being supplemented through the instrumentality of the universal joints 35 and 36 which make possible the articulated shafts which support and guide the sleeve holders of the sleeve layer described.

Operation of the detent means of Fig. 5 again locks the parts for convenient access by the operator as previously explained.

Although the above description relates to a preferred construction and arrangement of the sleeve layer of this invention as portrayed in the accompanying drawings, changes in the general

combinations and in the individual elements are contemplated which are within the scope of the appended claims. All such modifications shall be governed by the breadth and scope of the claims as will the substitution of equivalent mechanisms to function in the capacity of the mechanisms comprising the disclosed device.

What I claim is:

1. A sleeve layer adapted for use between two adjacent presses comprising a pair of sleeve holders and operative means for actuating the sleeve holders from vertical sleeve receiving positions to horizontal flat operative pressing positions with respect to said presses, said operative means including mechanism to tilt the sleeve holders forwardly and outwardly with respect to the heated parts of said presses to facilitate removal of the sleeves from the holders without injury to the operator.

2. A sleeve layer adapted for use between two adjacent presses comprising a bracket to connect said presses in predetermined positions with respect to each other, operative means mounted on said bracket and in fixed relation to both presses, and a pair of sleeve holders connected with said operative means for the upright reception of sleeves to be ironed by said presses in horizontal position, said operative means including mechanism to tilt the sleeve holders forwardly and away from said presses under actuation by said operative means.

3. A sleeve layer adapted for use between two adjacent presses positioned with their bucks in line, comprising a support disposed between said presses, operative means carried by said support, and a pair of sleeve holders connected with said operative means to receive sleeves to be ironed, said operative means including rotatable elements for said sleeve holders to actuate the latter from upright sleeve receiving positions to horizontal operative ironing positions with respect to said bucks, and said elements having tilting mechanism connected therewith to move the sleeve holders into forwardly tilted relation with respect to said bucks of the presses when actuated into sleeve handling position.

4. A sleeve layer adapted for use between two adjacent presses comprising a bracket to connect said presses in predetermined positions with respect to each other, operative means mounted on said bracket and in fixed relation to both presses, and a pair of sleeve holders connected with said operative means for the upright reception of sleeves to be ironed in horizontal position by said presses, said operative means including mechanism to tilt the sleeve holders forwardly and away from said presses under actuation by said operative means, and automatic detent mechanism connected with said operative means to lock the latter and said sleeve holders in sleeve receiving positions.

5. A sleeve layer adapted for use between a pair of ironing presses having bucks and heated shoes, comprising a pair of rotatable members supported between said presses, sleeve holders carried by said rotatable members respectively, operative actuating mechanism connected with the aforesaid members at one end to rotate the latter in opposite directions to displace said sleeve holders from substantially vertical positions to operative positions upon the bucks of the presses, and means connected with the other ends of said rotatable members to tilt said members and said sleeve holders during actuation by said operative mechanism from buck positions to

sleeve handling positions whereby said sleeve holders are tilted forwardly and away from the heated shoes during the handling of the sleeves by the operator.

5. A sleeve layer adapted for use between a pair of ironing presses having bucks and heated shoes, comprising a pair of rotatable members supported between said presses, sleeve holders carried by said rotatable members respectively, operative actuating mechanism connected with the aforesaid members at one end to rotate the latter in opposite directions to displace said sleeve holders from substantially vertical positions to operative positions upon the bucks of the presses, and means connected with the other ends of said rotatable members to tilt said members and said sleeve holders during actuation by said operative mechanism from buck positions to sleeve handling positions whereby said sleeve holders are tilted forwardly and away from the heated shoes during the handling of the sleeves by the operator, and releasable locking means connected with said operative mechanism to counteract accidental movement of said sleeve holders by the operator during handling.

7. A sleeve layer for use between a pair of presses comprising a pair of parallel shafts, sleeve holders connected with said shafts for direct rotation therewith, gear means to rotate said shafts in opposite directions to actuate said sleeve holders from upright positions to coplanar positions in ironing relation to said presses, and coacting cam mechanisms connected with said shafts to tilt the same during the actuation of said sleeve holders between said two positions, said shafts being substantially disposed in the same plane with the sleeve holders when the latter are in ironing positions, and said shafts being in their maximum positions of tilt when said sleeve holders are in upright positions and tilted in a direction to dispose said sleeve holders forwardly and outwardly with respect to said presses.

8. A sleeve layer for use between a pair of presses comprising a pair of parallel shafts, sleeve holders connected with said shafts for direct rotation therewith, gear means to rotate said shafts in opposite directions to actuate said sleeve holders from upright positions to coplanar positions in ironing relation to said presses, and coacting cam mechanisms connected with said shafts to tilt the same during the actuation of said sleeve holders between said two positions, said shafts being substantially disposed in the same plane with the sleeve holders when the latter are in ironing positions, and said shafts being in their maximum positions of tilt when said sleeve holders are in upright positions and tilted in a direction to dispose said sleeve holders forwardly and outwardly with respect to said presses, and said gear means having a manual control handle to rotate said gears upon rotation of said handle.

9. A sleeve layer for use between a pair of presses comprising a pair of parallel shafts, sleeve holders connected with said shafts for direct rotation therewith, gear means to rotate said shafts in opposite directions to actuate said sleeve holders from upright positions to coplanar positions in ironing relation to said presses, and coacting cam mechanisms connected with said shafts to tilt the same during the actuation of said sleeve holders between said two positions, said shafts being substantially disposed in the same plane with the sleeve holders when the lat-

ter are in ironing positions, and said shafts being in their maximum positions of tilt when said sleeve holders are in upright positions and tilted in a direction to dispose said sleeve holders forwardly and outwardly with respect to said presses, and a manually operable handle connected with said gear means to actuate the latter, said handle being arranged for movement from an upright position to a horizontal position to move said sleeve holders in the same relation, and releasable automatic lock means to restrain movement of said handle and the sleeve holders while in upright positions.

10. A sleeve layer for use between a pair of presses comprising a pair of parallel shafts, 15 sleeve holders connected with said shafts for direct rotation therewith, gear means to rotate said shafts in opposite directions to actuate said sleeve holders from upright positions to coplanar positions in ironing relation to said presses, and 20 coacting cam mechanisms connected with said shafts to tilt the same during the actuation of said sleeve holders between said two positions, said shafts being substantially disposed in the same plane with the sleeve holders when the 25 latter are in ironing positions, and said shafts being in their maximum positions of tilt when said sleeve holders are in upright positions and tilted in a direction to dispose said sleeve holders forwardly and outwardly with respect to 30 said presses, and a manually operable handle connected with said gear means to actuate the latter, said handle being arranged for movement from an upright position to a horizontal position to move said sleeve holders in the same relation, and releasable automatic lock means to restrain 35 movement of said handle and the sleeve holders while in upright positions, said lock means comprising separable elements to release said lock means upon bodily actuation of said handle at 40 right angles to its normal plane of operation to move the sleeve holders.

11. A sleeve layer comprising movable means supported between two presses, sleeve holders connected with said movable means, operative means connected to actuate said movable means relative to said presses to preposition said sleeve holders, said operative means being adapted to move said sleeve holders from upright sleeve-receiving position to horizontal pressing position upon said presses, and mechanism to lock said operative means against movement while said sleeve holders are in sleeve receiving positions.

12. A sleeve layer for moving a pair of garment sleeves from an upright adjacent position into oppositely outwardly horizontal positions, comprising a pair of shafts, sleeve holders carried by said shafts, a gear mechanism to rotate said shafts in opposite directions, means interposed between said shafts and said gear mechanism to allow said shafts to swing relatively to the gear mechanism, guide means to control the paths of movements of the swingable ends of said shafts, and cam mechanism to swing said shafts into positions during the operation of said gear mechanism whereby said sleeve holders are shifted into predetermined selected positions for the convenience and safety of the operator during the application or removal of the garment sleeves from the sleeve holders.
